New York, N. Y., a corporation of New York

Application March 5, 1938, Serial No. 194,047

9 Claims. (Cl. 263—47)

This invention relates to a container and more particularly to a container for reels or coils of wire during heat treating.

In the wire annealing industry solid flat steel plates have been used in some cases for supporting reels of wire of the type which are of such weight as to require cranes to move them in and while being transformed to and from the furnace. When such plates are used they are rather thick, to supply sufficient strength to support stacks of such reels, and in addition to the fact that the plates do not prevent the reels from falling therefrom when being transferred to and from the furnace they absorb considerable heat from the furnace, thus affecting the time required for annealing and cooling the wire.

An object of the invention is to provide a container for more efficiently, practically and expeditiously transporting reels or coils of wire.

With this and other objects in view, the invention comprises an open metal frame substantially cylindrical in contour and divided by vertical partitions into reel receiving compartments surrounding a central reel receiving compartment, the partitions having inclined guide portions projecting above the frame to guide the reels into the compartments during loading.

Other objects and advantages will be apparent from the following detailed description taken in conjunction with the accompanying drawing, wherein

Fig. 1 is a perspective view of the container, portions thereof being broken away;

Fig. 2 is a fragmentary sectional view taken along the line 2—2 of Fig. 1; and

Fig. 3 is a fragmentary sectional view taken along the line 3—3 of Fig. 1.

Referring now to the drawing, a frame or hollow body portion, cylindrical in general contour, is composed of annular horizontal elements 11, 12, 13 and 14 secured, in spaced positions, to vertical elements 16. The annular elements are formed of flat strips of metal, bent into circular formation and secured to the several vertical elements. The various parts of the container are formed of sheet metal of desirable gages and are secured to their respective parts by welding or any other suitable means. The vertical elements 16 are also formed of flat strips of metal, and in addition to being secured to the annular elements 12, 13 and 14 are secured at their lower ends to the annular element 11, which in the present instance is angular in cross section, forming a supporting edge 17 for the container and an annular shoulder upon which a sheet metal

plate forming the bottom member 18 of the container is disposed and to which it is secured.

In the present embodiment of the invention the frame is divided into seven compartments, six of these compartments bearing reference numerals 21, 22, 23, 24, 25 and 26 being positioned circumferentially about a center compartment 27. The bottom member 18 is provided with a relatively large aperture 30 for each compartment, the axis of each aperture being in substantial alignment with the axis of a stack of reels when disposed therein. The diameters of the apertures are less than the diameters of the reels to provide supporting ledges at the bottom of each compartment, yet allowing an open space through the apertures for the free circulation of atmosphere. To further assist in the circulation of atmosphere around coils in the compartments, a multiplicity of smaller apertures 32 is formed in the bottom portion around each of the larger apertures 30.

The compartments 21 to 27 inclusive are formed in the frame by sheet metal members formed with a multiplicity of apertures to reduce the material therein and allow free circulation therethrough. One of these members indicated at 35 extends from an edge 36, where it is secured to the annular elements 11 to 14 inclusive, at an angle to the position indicated at 37, where it is bent to extend radially of the annular frame 30 to a position 38, from which position it extends semi-circularly about the center line of the frame to a position 39, where it terminates. A substantially identically formed strip of sheet metal 42 extends at an angle from a position 43, where it is secured to the annular elements 11 to 14 inclusive, to a position 44 where it is bent at an angle and extends radially in alignment with its corresponding member to the position 39, where it is secured to the end of its corresponding member, and from this position it extends semi-circularly to the position 38, where it is secured to its corresponding member. The two members 35 and 42 form the central circular compartment 27 and provide partitions for dividing compartments 21—23 and 25—26.

Smaller sheet metal plates 45 and 46 extend at angles from positions 37 and 44, respectively, to which their inner edges are secured, to the annular members 11 to 14 inclusive, to which their outer edges are secured.

It will be observed that the member 35 forming one half of the central compartment 27 extends above the hollow body portion the purpose being to provide abutting guides for the compartments 21—23 and 25—26.

21, 22 and 26 when placing reels or coils of wire in these compartments. In order to provide an abutting guide for the central compartment the semi-circular portion of the member 42 is extended upwardly from the upper edge of the semi-circular portion of the member 35, as indicated at 48, the outer edges of the portion 48 extending in reverse arcs, as at 49 and 50, to further assist in guiding reels into substantial alignment with the central compartment 27. The semi-circular portion 42 including the extended portion 48 provides abutting guides for the compartments 23, 24 and 25. Partitions 55, 56, 57 and 58 extend radially from their respective semi-circular members 35 or 42, to which their inner edges are secured, to the annular elements 11 to 14 inclusive, to which their outer edges are secured.

Positioned in the spaces formed by the plates 20 45 and 46, the angular portions of the members 35 and 42 and the adjacent portions of the annular elements are annular hook receiving sockets or members 60, their inner ends being closed by metal plates 61 and secured with the plates 25 to the adjacent portions of their respective strips and members, while their outer ends extend through apertures in diametrically opposed vertical elements 16, to which they are secured. The angular formations of the partition members 30 35 and 42 and their associated members 45 and 46 serve to protect the hook receiving members 60 from reels or coils of wire when disposed in the adjacent compartments. The purpose of the hook receiving members is to receive suitable 35 hooks or attachments of a crane when transporting the container to and from a furnace.

The container is designed primarily for use in holding a plurality of reels or coils of wire of the type which, due to their weight, require the 40 assistance of a crane to transport them to and from a furnace during the heat treatment thereof. The upper edges of the partitions 55 to 58 inclusive, as well as the upper edges of the portions of the members 35 and 42, serving as partitions between the compartments 22-23 and 45 25-26 extend upwardly from points adjacent the upper edge of the frame 18 to points at their inner extremities in a common plane with the uppermost edge of the member 35. These upper 50 portions of the radially extending partitions serve as guides when moving the reels into registration with the compartments.

Let it be considered, for example, that the operator wishes to fill compartment 21 first. A 55 crane equipped with means (not shown) to engage the reels, as, for example, through their hollow hubs, may be employed in lifting the reel of wire to move the lower edge of the reel above the upper edge of the frame, then by moving the reel laterally toward the center of the container the lower head of the reel will be guided by the angular portions of the partitions 55 and 58 until the reel abuts the portion of the partition member 35, at which time the operator will know 60 that the reel is in alignment with and may be lowered into the compartment 21. Other reels of wire may be similarly lowered into the compartment 21 until this compartment is filled, then by directing reels to the other compartments 22, 23, 24, 25 and 26 these compartments may be filled 65 with reels in a similar manner.

A special abutting member 48 is provided for the central compartment 27 and this compartment may be filled by moving the reels first, vertically to a position above the upper edge of

the member 35, and then, laterally toward the center of the container until they abut against the portion 48, at which time they may be lowered into the central compartment. After the container has thus been filled with reels, or, if desired, coils of wire, it may be raised by the aid of a crane, the lifting hooks of which are engaged in the members 60 to transport the container with its contents to a furnace.

The container has been designed primarily for use in electric bell-type inert gas heat treating furnaces, but it should be understood that the container may be used to transport articles to and from and into and out of furnaces of any desired type. The container is sufficiently durable to withstand the weight of several reels, yet it is sufficiently light and formed of the least possible metal so that the amount of heat which it absorbs from the heating elements of the furnace is reduced to a minimum, thus reducing to a minimum the time required for heat treating and cooling the wire on the reels. Furthermore, the frame is composed of the spaced annular and vertical members forming large spaced apertures therein, and the bottom member and partitions are formed with apertures for the free circulation of atmosphere through the container and around the reels. The provision of these apertures reduces the weight of the container per se, the material therein to thus reduce the heat absorbed thereby, and allows free circulation of air through and around the contents of the container. With the container it is possible to transfer sacks of reels to and from the furnace more readily without danger of the reels shifting or becoming dislodged therefrom.

Although the invention is herein disclosed as a container for transporting reels and coils of wire to and from a furnace it is obviously not so limited but is applicable to other fields. The invention is limited only as to spirit and scope by the appended claims.

What is claimed is:

1. A container for transporting articles comprising a hollow body portion, a bottom portion therefor, a central partition fixed in the body portion to form a central article receiving compartment, and partitions fixed to and extending transversely from the central partition to form outer article receiving compartments in the body portion around the central compartment, the central partition extending above the body portion and serving to guide articles into the outer compartments.

2. A container for transporting heavy articles comprising a hollow body portion, partitions disposed in the body portion to form compartments therein and formed to vertically align laterally moving articles with the compartments, and lifting hook receiving members fixed to the body portion.

3. A container for transporting heavy articles comprising a body portion with apertured side walls and bottom portion, partitions disposed in the body portion to form compartments, the apertures in the bottom portion being substantially centrally disposed relative to their respective compartments to form supporting ledges for articles disposed in the compartments.

4. A container for transporting heavy articles to be heat treated comprising a body portion formed of spaced annular strips secured to spaced vertical strips, and an apertured bottom portion, and radially extending partitions disposed in

- the body portion to divide the latter into a plurality of compartments.
5. A container for transporting heavy articles to be heat treated comprising a body portion formed of spaced annular strips secured to spaced vertical strips and an apertured bottom portion, an annular partition disposed in and extending above the body portion to form a central compartment therein, and radially extending partitions disposed in the body portion and having upper edges extending upwardly from the upper edges of the body portion.
10. A container for transporting heavy articles to be heat treated comprising a body portion formed of spaced annular strips secured to spaced vertical strips and an apertured bottom portion, an annular partition disposed in and extending above the body portion to form a central compartment therein, and radially extending partitions disposed in the body portion and having upper edges extending upwardly from the upper edges of the body portion, one portion of the annular partition extending above the other portion thereof.
15. 7. A container for transporting articles com-

prising a body portion having an open end, and partitions fixedly disposed in the body portion to form compartments therein and having their upper edges extending above the said open end to align laterally moving articles with the compartments.

8. A container for transporting articles comprising a body portion having an open end, walls forming a central compartment disposed in the body portion and extending above the open end thereof, and partitions extending radially from the said walls in the body portion and above the said open end to form article receiving compartments.

9. A container for transporting articles comprising a body portion having an open end, walls forming a central compartment disposed in the body portion and extending above the said open end with one wall extending above another to form a guide, and partitions extending radially from the said walls in the body portion and above the said open end to form article receiving compartments and guide articles to the compartments.
